PRESS FOR WATCH CRYSTALS

Henry A. Mintz, Norwood, Mass.

Application February 16, 1937, Serial No. 126,007

4 Claims. (Cl. 81—6)

This invention relates to a device for pressing watch crystals in bezels and at the same time applying a moderate heat to set the crystal more firmly in the bezel.

5 The device hereinafter described is useful in setting crystals of any kind, particularly unbreakable crystals which are made of transparent Celluloid or other equivalent non-shatterable material. Watch crystals of this material are 10 commonly used in wrist watches, since such watches are liable to receive accidental blows. However, when such crystals are inserted in a bezel in the usual manner, they are ordinarily distorted and are therefore liable to spring out 15 of the bezel if struck, particularly if the bezel itself is even slightly out of shape. It is an object of this invention to remove this tendency to spring out by cementing the edges of the crystal into the groove of the bezel and by heating the 20 crystal sufficiently to destroy the internal stress of the crystal. Crystals of this type are customarily convex and are made with sufficient curvature to enable the central portion to bulge away from the face of the watch, thus providing 25 plenty of room for the watch hands.

It is a further object of the invention to provide a simple but effective pressing device whereby a constant pressure may be applied to the central portion of a mounted crystal, so as to 30 press the edges of the crystal firmly into the groove of the bezel during the drying and setting of the cement which is inserted in the groove of the bezel before the crystal is set therein. The press is also provided with a heating element 35 conveniently arranged to heat the crystal and bezel while they are being pressed.

For a more complete understanding of the invention, reference may be had to an embodiment thereof which is hereinafter described and which 40 is illustrated on the drawing of which

Figure 1 is a side elevation of a device embodying the invention.

Figure 2 is a section on the line 2—2 of Figure 1.

45 Figure 3 is a section on the line 3—3 of Figure 2, a heating unit being shown in this figure.

Figure 4 is a section on the line 4—4 of Figure 1.

50 Figure 5 is a fragmentary front elevation of the device shown in Figure 1.

The device may include a unitary support frame comprising a base 10 from which rises a standard or upright 12. A lower bracket 14 and an upper bracket 16 project from the upright 12 and 55 are vertically spaced from each other. A plat-

form member 20 is secured to the end of the lower bracket 14 as by a pair of screws 22 so that this platform projects horizontally from the bracket. The upper bracket is of sufficient length to project out over the platform 20. Through the 5 upper bracket is screw-threaded a stem 24 having a knurled upper end 26 to facilitate rotation thereof. The lower end portion 28 of this stem projects down toward the platform 20 and may be made to approach or recede from the 10 platform by rotation of the stem. A press-plate 30 is spaced above the platform 20 and is engageable by the lower end of the stem 24. This press-plate may be of any convenient construction and may be supported in any convenient manner. As 15 shown, this plate is elongated, one end portion of the plate having a perforation 32 in which loosely fits a post 34. This post is mounted in the upper bracket and projects down to the lower bracket. This arrangement makes it possible to 20 swing the press-plate 30 over or away from the platform 20 and to move it up and down freely on the post 34. The lower bracket is provided with a bore 40 extending horizontally therefrom from the rear face of the upright 12. This bore 25 registers with a bore 42 which extends most of the way through the platform member 20. As indicated in Figure 3, the bores 40 and 42 are adapted to receive a suitable heating unit 50 having a coil or equivalent heating element 52 in 30 the forward end thereof which fits snugly in the bore 42. This unit may be held in place by any convenient means such as a bushing 53 of Bakelite or other convenient material, secured as by a setscrew 54 in a hollow boss 56 which projects 35 from the rear face of the upright 12. The rear end of the heating unit 50 may be tapered so as to center the unit as the tapered end is pulled into the bore of the bushing 53. For this purpose a spring 58 may be employed, if desired, the 40 spring extending to a control switch (not shown) so as to remain under compression. The spring 58 also serves to protect the connecting wires 59 which lead from the unit 50 to its control switch. The bore 40 is preferably somewhat larger in 45 diameter than the heating unit 50 so as to avoid contact of the unit with the walls of the bore, the purpose of this being to avoid excessive heating of the bracket 14. To this end also, the end of the bracket is recessed by a horizontal channel 61 and a pair of vertical channels 60 so that the table member 20 bears against the end of the bracket 14 at only a few spaced points to provide simple but effective thermal insulation between the table and the bracket. 55

In using the device for setting a crystal, the bezel of a watch, if removable from the rest of the watch case, is placed upon the platform 20 either face up or face down, the former position being preferred. The bezel is located so that the center of the crystal is directly beneath the stem 24, the stem being previously rotated to back the end 28 away from the platform sufficiently to provide room for the watch bezel. 5 The press-plate 30 is then swung into position over the crystal and the stem 24 is rotated so as to press the end 28 against the plate 30, forcing the plate down firmly against the central portion of the crystal until the edges of the crystal are pressed firmly into the groove of the bezel. 10 The bezel or watch case is then left clamped in this position for a sufficient period to permit the crystal to be warmed and the cement to set. The stem 24 is then raised to permit the removal of the bezel or case from beneath the plate 30. 15

In setting unbreakable watch crystals, I prefer to use a cement made of material similar to that of the crystal dissolved in a suitable volatile solvent. 20 Such cement, when set, becomes integral with the crystal itself, resulting in a unitary crystal the edges of which exactly fit into the grooves of the bezel and bond therewith.

In some cases, the bezel or watch case is arcuate or has a portion of the hinge or some other part of the case projecting below the plane of the bottom of the case or the edge of the bezel. In order to avoid injury to the watch case which might result from pressing such a case against 30 a flat surface, an auxiliary support member 70 is provided. This may be of any convenient size or shape. As shown, the support 70 consists of a bar of metal having a perforation 72 in one end portion thereof through which extends the 35 post 34, so that the support member 70 can be swung into position upon the platform member 20, as indicated in Figure 5, or may be swung away as indicated in Figure 1. Figure 1 shows a watch case 74 with a flat back supported directly on the platform 20. Figure 5 shows an arcuate watch case 76 supported on the auxiliary support member 70. The use of the narrow auxiliary support avoids danger of injury to the watch case. 45

50 It is evident that various modifications and changes may be made in the specific embodiment of the invention herein shown and described without departing from the spirit or scope of the invention as defined in the following claims. It

is further noted that terms, such as "horizontal", "vertical" and the like, are terms of description and not of limitation, and that the device may be used in any convenient position desired. 5

I claim:—

1. A device of the class described, comprising a platform, heating means within said platform, an auxiliary support member of heat-conducting material movable on and off said platform, a press-plate above said platform, and means for 10 pressing said press-plate toward said platform.

2. A device for pressing watch crystals in bezels, comprising a supporting frame having a base, an upright, and a pair of vertically spaced brackets on said upright, a platform projecting horizontally from the lower bracket and heat-insulated therefrom, heating means within said platform, a press-plate above said platform, and means carried by the upper bracket for pressing said plate toward said platform. 15

3. A device for pressing watch crystals in bezels, comprising a supporting frame having a base, an upright, and a pair of vertically spaced brackets on said upright, a platform projecting horizontally from the lower bracket and heat-insulated therefrom, a post fixed to said lower bracket and projecting upwardly therefrom, a press-plate having a perforation loosely receiving said post, said plate being of sufficient length to extend over said platform, and a stem screw 30 threaded through the upper said bracket and projecting toward said platform and engaging said plate, whereby said stem may be rotated to press said plate toward said platform. 20

4. A device for pressing watch crystals in bezels, comprising an upright, a pair of vertically spaced brackets projecting from said upright, a platform projecting from the lower of said brackets, an electric heating unit extending through said upright and lower bracket into 40 said platform so as to heat said platform, a post fixed to said lower bracket and projecting upwardly therefrom, an elongated auxiliary support member and an elongated press-plate, said member and plate each having in an end portion 45 thereof a perforation in which said post loosely fits, whereby said member and plate can be independently swung over or away from said platform, and a vertical stem directly above said platform and screw-threaded through the upper 50 bracket and engaging said plate so as to press said plate toward said platform when said stem is rotated.

HENRY A. MINTZ.
